UNITED STATES PATENT OFFICE.

DONALD M. NAISMITH, OF PITTSBURGH, PENNSYLVANIA, ASSIGNOR, BY MESNE ASSIGNMENTS, OF ONE-HALF TO THE MCALLEMAN CORPORATION, OF PITTSBURGH, PENNSYLVANIA, A CORPORATION OF PENNSYLVANIA.

BOILER.

Application filed February 14, 1921. Serial No. 444,678.

To all whom it may concern:

Be it known that I, DONALD M. NAISMITH, a citizen of the United States, residing at Pittsburgh, in the county of Allegheny and 5 State of Pennsylvania, have invented certain new and useful Improvements in Boilers, of which the following is a specification.

My invention relates to improvements in the construction of water tube boilers, and 10 more particularly that class of boilers where the superimposed drums or heads are connected with lower mud drums or heads by plural banks of circulating tubes for the production of steam.

15 The particular feature of invention involved herein is the provision of a drum interposed between adjacent steam drums and in the course of circulation of steam, or of steam and water, in its passage to the final 20 steam collecting drum, whereby to provide an intermediate separating chamber for effecting complete separation of any entrained water from the steam and delivery of resulting dry steam at the steam nozzle, even 25 though the feed water may contain impurities which would cause foaming or priming in other constructions of boilers. The invention has in view to effect such desirable separation of entrained water from the 30 steam and also the prevention of any water entering the superheater, if used.

In the drawings, which illustrate certain preferred embodiments of the invention, the boiler is represented merely in cross section through the complete boiler setting, it being understood that the extent of the several drums and their banks of tubes may be to any desired degree lengthwise of the boiler unit, and that further illustration of such 40 construction is unnecessary to those familiar with this art.

In the drawings,—

Fig. 1 is a view in cross section through a boiler setting constructed according to my 45 invention;

Fig. 2 is a detail sectional view showing means for protecting the intermediate separating drum and omitting any baffling walls;

50 Figs. 3 and 4 are detail sectional views showing various arrangements of baffling walls in connection with the standard drum and connecting tube construction;

Fig. 5 is a sectional detail view showing

a modified construction of intermediate 55 drum and the circulation of a portion of the gases therethrough from the furnace and back to the main circulation; and

Fig. 6 is a further sectional detail view showing the steam delivery drum provided 60 with a perforated partition.

The entire boiler unit, as is usual, is enclosed within a setting utilizing supporting and closing walls 2 with any suitable furnace construction 3, and, if desired, fuel 65 supply mechanism 4 of any appropriate type. Suitable outlet connection for the gases of combustion leading to the stack are, of course, utilized but are not necessarily herein specifically illustrated or described. 70

The construction as illustrated utilizes a main upper water inlet and steam supply drum 5, a lower mud drum 6, an upper water and steam drum 7, and an intermediate steam separating drum 8. Primary 75 drum 5 and mud drum 6 are connected by the bank of tubes 9, and drum 6 and drum 7 are connected by the associated banks of tubes 10 and 11, providing for main circulation of the water downwardly through tubes 80 9, then upwardly through bank of tubes 10 to drum 7, and downwardly through tubes 11 to drum 6.

Drum 8, which is the novel feature of the invention, is located entirely outside of the 85 water circulatory system, and is furthermore elevated entirely above the water level of drums 5 and 7. As shown, drum 5 is also considerably higher and with a proportionately greater open area than drum 7, the 90 cross area of which is submerged to about its middle, as shown. Series of tubes 12 connect the upper portion of drum 7 with drum 8 for carrying over into said drum steam from drum 7, together with any entrained water therein. Similar tubes 13 connect the opposite side of drum 8 with primary drum 5, whereby dry steam disassociated from any water content whatever, is carried over from drum 8 and delivered to the 100 steam containing drum 5 having the usual outlet connection 14. If desired, tubes 13 may be increased to any desired number, as at 13^a, Fig. 3, whereby to reduce the velocity of the steam in its passage toward 105 drum 5.

Connected with the lower portion of drum 8 and leading over to the lower side

portion of drum 5; preferably below the water level thereof, are the tubes 15 by which any water separated from the steam in drum 8 is returned directly to the water 5 circulatory system through drum 5. In a similar manner, series of tubes 16 connect drum 7 with drum 5 preferably below the water level of each, whereby to provide for transverse circulation of water from one 10 to the other. These, however, may be omitted, if desired, without materially affecting the operation. The lower most drum 6 is provided with a blow-off and drain pipe 17 for the purpose of completely 15 emptying the entire boiler, cleaning the mud drum, etc.

In the construction shown in Fig. 1, baffle plates or walls 18, 19, 20 and 21 are located at the positions and heights illustrated, together 20 with additional supplemental baffling walls or plates at various locations, as shown, whereby to provide for the circulation of gases of combustion, as indicated by the arrows through the several banks of 25 tubes and lengthwise of them, as well as against the lower drum 6, the gases finally passing out underneath upper drum 5 and between the individual tubes 9 to the outlet stack.

30 Incidentally, drum 8 may be provided with a deflecting or baffle plate or abutment 22 whereby to interfere with the direct progress of steam, or steam and water passing over through tubes 12, so as to break up 35 its passage directly to the tubes 13 leading to drum 5. By this construction, any remaining associated water is thoroughly and effectually separated, and will drain off through tubes 15.

40 The steam and water being thus separated in drum 8, the dry steam then passes through tubes 13 to drum 5, for collection and use, as desired. The particular purpose of the tubes 16 between drums 7 and 45 5 is to relieve any tendency of the water in drum 7 to pile up or accumulate therein, allowing it to freely pass over to drum 5 and into the circulation.

The importance and advantage of the desirable 50 circulation of steam and water effected by the construction within and through the several elements above described, will be appreciated from the fact that the steam is first retrieved or collected 55 in the substantially half drum space of drum 7, from whence it is then carried over into the full area or space of drum 8, reserved entirely for steam where complete and positive separation of any entrained 60 water is effected. From this drum, it is then conveyed over to the comparatively large space of drum 5 which is considerably more than half of its cross sectional area or drum space, so that the tendency 65 of the steam to separate from any associated

water and to collect in an entirely dry form in the final delivery drum 5 is positively assisted and effected. Feed water may be initially supplied to the circulation by a pipe 23, connected with drum 5 below 70 the water line, as shown.

By reason of the construction and arrangement of the three drums 7, 8 and 5, and of plural tubes 13^a when used, the velocity of the steam is slowed down to a comparatively low rate in drum 8 and also in drum 5 before it reaches the steam nozzle. Drum 8 being thus isolated entirely out of the water circulatory system, offers its full volume for the slowing down and water separating process.

The baffle 24, as shown in Fig. 1, completely encloses the space between drums 7 and 5 above the tubes 16 and below tubes 12, 13 and 15 and drum 8, so that drum 8 85 and said tubes are protected from the direct heat of the gases. However, baffle 24 or any portion of it may be omitted if desired, so as to utilize the gases of combustion with relation to these elements. In 90 Fig. 2, I show the baffle entirely omitted, but with a protecting covering 25 around the under side of drum 8, supported in any suitable manner, as by straps 26 depending from the construction.

In Fig. 3, I show a portion only of the baffle wall as 24^a at one side, exposing tubes 15 and 13 or 13^a to the gases, while Fig. 4 shows an alternative arrangement of baffle 24^b exposing tubes 12. The construction otherwise is as already described, and the several parts are similarly identified by corresponding numerals having the exponent *a* and *b* respectively. It will be understood, of course, that any other variation or disposition of the baffling walls may be utilized 105 so as to vary the heating effect as desired, within the judgement of the designer or builder.

Fig. 5 shows the intermediate drum 8^c 110 of a modified construction, utilizing vertical transverse gas circulation tubes 27 and with an outer enclosing wall 28. In such case, the gas circulation is upwardly through a valve-controlled port 29 and thence over 115 to and through the tubes 27 of the drum 8^c, and then downwardly as already described. In this arrangement, I may utilize any number of individual drums 8 or 8^c connected with drums 7 and 5 by the transverse steam 120 tubes 12 and 13 and with drum 5 by the lower water tubes 15, and operating in the same manner as already described.

In Fig. 6 I show a further modification in which the drum 5 is provided with the 125 customary feed water supply pipe 23 entering at any suitable point below the upper steam collecting chamber 30. A perforated partition 31 extends across the middle portion of drum 5 and separates its lower water 130

containing portion from the upper steam collecting chamber, above the water inlet. This partition tends to segregate the water and steam cavities but, of course, is not necessarily utilized. The usual steam outlet 32 is connected with the upper portion of drum 5, as shown.

The construction and operation of the boiler will be readily understood and appreciated by all those familiar with the art. The general arrangement of the several drums and circulating tubes provides for ample and thorough application of the heat of the furnace gases, and for the inclusion 15 of any suitable or standard form of super-heater, as indicated at 33. The entire construction is very compact in design and the steam generating elements have their heating surfaces so presented to the path of the 20 gases that they are utilized in the most efficient way. The several elements are proportionately arranged for the best results as to installation, location of the several 25 baffling walls, repair or replacement of tubes, etc. The drum 8 provides for complete separation of the entrained water from the steam and consequent delivery of dry steam even though the feed water might contain impurities which would cause foaming or priming in other boilers.

A great advantage in this respect is the prevention of slugs or entrained water entering the super-heater. A further advantage is the possibility of obtaining a super- 35 heating effect during the travel of the steam from drum 7 through tubes 12 to drum 8 and from drum 8 through tubes 13 to drum 5. As shown, this super-heating effect may be regulated by varying the baffling to close 40 off any portion of the heating surfaces.

The rear bank of tubes 9 contributes to economy of the heat, while an uninterrupted circulation is provided upwardly through tubes 10 and downwardly through tubes 45 11, in the zone of greatest heat. The invention also provides for a very efficient baffling, a highly desirable super-heater location, and a very practicable furnace action.

50 What I claim is:

1. In a water tube boiler, the combination with two outermost upper water circulation drums each having downwardly circulating heating tube connections with 55 a lower mud drum, one of said drums having a steam outlet connection, of an intervening isolated steam separating drum elevated above the water level of said drums and having steam connection to both of 60 said drums.

2. In a water tube boiler, the combination with two outermost upper water circulation drums, one having an outlet connection and constituting the final steam supply 65 drum, a lower mud drum, and independent

banks of downwardly circulating water tubes connecting each water circulation drum with the mud drum, of a water separating steam drum located between the upper drums above the water level thereof and 70 having steam receiving connection with one of the outermost drums and steam supply connection with the other or final steam supply drum.

3. In a water tube boiler, an upper drum 75 in water circulation with the heating elements of a boiler unit and provided with a water inlet and a steam outlet connection, an opposite upper drum also in water circulation with the heating elements of a 80 boiler unit, and a drum intervening between said drums above the water level thereof having steam receiving connection with said opposite drum and steam supply connection with the other drum having the water 85 inlet and steam outlet connection.

4. In a water tube boiler, an upper drum in water circulation with the heating elements of a boiler unit and provided with a water inlet and a steam outlet connection, 90 an opposite upper drum also in water circulation with the heating elements of a boiler unit, and a drum intervening between said drums above the water level thereof having steam receiving connection with said 95 opposite drum and steam supply connection and return water connection with the other drum having the water inlet and steam outlet connection.

5. In a water tube boiler, the combination 100 of two outermost drums each in water return circulation with the heating elements of a boiler unit, one constituting a water receiving and steam supply drum and provided with a steam outlet connection, of an 105 intervening water separating steam drum having steam receiving connection with one of said outermost drums and an interior obstructing baffle plate extending across such connection, steam supply connection with the other or steam supply drum, and a lower baffle in protective relation to said intervening drum.

6. In a water tube boiler, the combination with a pair of upper drums in water 115 return circulation with a lower drum by series of banks of tubes, one of said upper drums having a water supply and a steam outlet, of a drum intervening between the upper drums elevated above the water level 120 and provided with steam receiving tubes connecting it with one of said drums and steam supply tubes connecting it with the other, a drain tube connecting the lower portion of the intervening drum with the 125 steam outlet drum, and a baffle arranged below said middle drum and circulation tubes.

7. In a water tube boiler, the combination 130 with a pair of upper drums in water circu-

lation with the heating elements of a boiler unit, one having a steam outlet connection, of an intervening steam separating drum having a steam receiving connection with one of said drums and a steam supply and drainage connection with the other or steam outlet drum.

8. In a water tube boiler, the combination with a pair of upper drums in water circulation with the heating elements of a boiler

unit, of an intervening steam separating drum having a steam receiving connection with one of said drums and a steam supply connection with the other, and a steam take-off connection with one of said upper water drums.

In testimony whereof I hereunto affix my signature.

DONALD M. NAISMITH.
